Primary Examiner — Karen E Eldridge Powers(74) Attorney, Agent, or Firm — Legalforce RAPC Worldwide(57) CLAIM

The ornamental design for a body scrubber, as shown and described.

DESCRIPTION

FIG. 1 is a top perspective view of a body scrubber, showing my new design;

FIG. 2 is a bottom perspective view of the design shown in FIG. 1;

FIG. 3 is a top plan view of the design shown in FIG. 1; and, FIG. 4 is a bottom plan view of the design shown in FIG. 1. The broken lines indicate unclaimed portions of the design and form no part of the claimed design.

1 Claim, 4 Drawing Sheets(56)
